UNITED STATES PATENT OFFICE.

ARTHUR FEINBERG, OF NEW YORK, N. Y.

STRESS-PRECLUDING ATTACHMENT FOR ARTIFICIAL DENTURES.

Application filed November 18, 1922. Serial No. 601,893.

To all whom it may concern:

Be it known that I, ARTHUR FEINBERG, a citizen of the United States, residing at New York city, borough of Manhattan, county and State of New York, have invented a certain new and useful Stress-Precluding Attachment for Artificial Dentures, of which the following is a specification.

10 This invention is an attachment for artificial dentures, and provides means whereby such dentures may be attached to natural teeth in such a manner as to preclude the transmission to the natural teeth or roots 15 all stresses and strains, which would be apt to, in time effect and cause loosening thereof.

It is well known in the practice of dentistry that when a bridge or plate work is anchored to natural teeth in a firm or 20 rigid manner, stresses and strains are communicated to the natural teeth from the artificial denture in such a way as to cause irritation and loosening of the natural teeth.

The attachment of my invention is so arranged and constructed as to remove or 25 take off all the strains of the natural teeth, and transmit them directly to the ridge or gums of the mouth, in other words the forces of mastication which are brought to 30 bear upon the artificial denture, are transmitted directly to the gums or ridge, and the natural teeth are availed merely for the purpose of maintaining the denture in position, the attachment maintains the artificial denture at all times in proper position and relation to the natural teeth and also engages with the gums and ridges so 35 that it does not permit the denture to draw away or become dislodged. Heretofore suggestions have been made to overcome these 40 difficulties, and the present invention relates to improvements on these devices, and obviate the difficulties and objections indicated, and more so to furnish a more simple and 45 efficient means for connecting an artificial denture to natural teeth.

It will be apparent from the hereinafter detailed description and claims, when read in conjunction with the accompanying drawings.

Figure 1 is a perspective view of a metallic plate to be firmly secured to the crown or clasp by means of soldering or otherwise, and is termed the clasp part.

50 Figure 2 is a similar view of a metallic plate to be rigidly secured or embedded in

the substance of a plate, and is termed the denture part.

Figure 3 is an assembled perspective of 60 the attachment.

Figure 4, is a plan showing the attachment applied to a clasp.

Figure 5 shows its application to natural teeth.

In the drawings, 10 designates the clasp part, consisting of a metallic plate to be firmly secured to the clasp or crown, by soldering or otherwise, and is bent at its lower end to form a leg 11, which is longitudinally slotted as at 12. The denture 70 part 13, comprises an upstanding metallic plate 14, which is bent laterally forming a tail piece 15. The upper part of plate 14 is bent at 16 to form a horizontal flange 18, which after a short distance is bent and continued downwardly in a straight line to form a tongue as at 17. The tail piece 15, being perforated as at 19, also has an integral, uprising flange shaped like a dovetail as at 20. The stop flanges 21 are integral, and continues from the tail piece 15, terminating at and engaging with the free ends of the tongue 17, as at Figure 2.

To assemble the parts 10 and 13, the stop flanges are slightly bent to permit the free end of the tongue 17 to pass through the aperture 12, as in Figures 1 and 3. The stop flanges 21 are then brought back to its original position, thereby preventing their separation. The clasp part 10 with 90 its leg 11 extending outwardly, is soldered or brazed to the side of the clasp 22, as in Figures 4 and 5.

In securing the denture part 13, with the artificial denture 5, the artificial denture is 95 brought to bear upon the tail piece 15 and against the plate 14 and over the flange 18, it is then vulcanized or soldered against either the tail piece 15, or plate 14, or both. The perforations and dove-tail of the tail 100 part 15 is for the purpose of the rubber denture, if such a denture is preferred, to have a better grip, as rubber when vulcanized against a smooth surface will not hold, so that if the tail part 15 is made smooth 105 without the perforations 19 or without the dove-tail 20, the rubber denture will yield, leave, or break away loose from the denture part 13.

The free movements of the artificial denture 5, is limited above by the flange 18 and below by the flanges 21.

It will be apparent from the foregoing description that all the forces and strains which are brought to bear upon the artificial denture when anchored to natural teeth in a rigid manner, will be relieved and removed from the natural teeth and transmitted to the gums or ridges. The clasp part only being rigid, while the plate part will yield slightly at either side, to vertical, tilting and transverse pressures produced by chewing. The parts here shown are greatly exaggerated, however in practice they are made very small.

Having fully described my invention, what I claim and desire to secure by Letters Patent is:

1. In a device of the class described, a dental attachment having a perforated clasp part, a denture part provided at one of its edges with a tongue being adapted to pass through the perforation of the clasp part, and at another of its edges with a tail

piece, said tail piece being perforated having an integral upstanding dove-tail part, and provided with two flanges terminating at and engaging with the tongue, thereby securing the clasp part with the denture part. 25

2. In a device of the class described, a dental attachment having a slotted clasp part, a denture part embodying a tongue which extends into the slot of the clasp part, and a perforated tail piece provided with flanges, said flanges terminate at right angles with the free ends of the tongue. 30

3. In a device of the class described, a dental attachment having a perforated clasp part, a denture part comprising a tongue which extends into and engages with the slot of the clasp part, said tongue extending upwardly and then bent over downwardly 40 upon itself forming a closed loop with the forward part of the tail piece.

ARTHUR FEINBERG.
